J. M. HILL.

SUPPORTER FOR RAIL ENDS,
APPLICATION FILED JAN. 9, 1917.

1,238,518.

Patented Aug. 28, 1917.

Attorney

UNITED STATES PATENT OFFICE.

JAMES M. HILL, OF LEXINGTON, VIRGINIA, ASSIGNOR OF ONE-HALF TO JOHN W. BOWEN,
OF BALTIMORE, MARYLAND.

SUPPORTER FOR RAIL ENDS.

1,238,518.

Specification of Letters Patent. Patented Aug. 28, 1917.

Application filed January 9, 1917. Serial No. 141,365.

To all whom it may concern:

Be it known that I, JAMES M. HILL, a citizen of the United States, residing at Lexington, in the county of Rockbridge and State of Virginia, have invented certain new and useful Improvements in Supporters for Rail Ends, of which the following is a specification.

This invention relates to a supporter for the rail-ends of railway track rails.

The object of the invention is to provide new and improved means for supporting the abutting ends of the track-rails of railroads, and thereby prevent said rail-ends from yielding downwardly as the wheels of a moving train of cars pass over said abutting rail-ends.

The rail-end supporter will first be described in connection with the accompanying drawing and the invention will then be pointed out in the appended claims.

In the said drawing—

Figure 1, is an elevation or side view showing the abutting ends of two track-rails, and the rail-end supporter in position.

Fig. 2, is a plan view of same in which the top surface is shown of one rail, and a horizontal longitudinal section of the web of the other rail is shown and the arms of the supporter bolted thereon, the section being taken on the broken line 2—2 of Fig. 1.

Fig. 3, is a vertical cross-section of a track-rail near its end, and also of the supporter device of the present invention, the section being taken on the line 3—3 of Fig. 2.

Fig. 4, shows a vertical cross-section of one rail and the two arms of the supporter, taken on the line 4—4 of Fig. 2. In the first four figures a screw is employed to raise the seat-plate.

Fig. 5, is a side view of two rail-ends and the supporter, but shows a modification for the screw to raise the seat-plate.

Fig. 6, is a vertical cross-section similar to Fig. 3, but showing the modified device that raises the seat-plate under the rail-end.

Referring now to the drawings the several parts shown will be described by the use of designating numerals.

The numeral, 7, designates the head or top surface of each track-rail; 8, the base of the rails, and 9, the vertical web that joins said base and head. The vertical line

10, seen in Figs. 1, 2, and 5, is the place of separation where the ends of two rails abut, and these are the rail-ends that are liable to yield downwardly under the weight of a moving train. The rails rest upon the 60 usual cross-ties, 11.

A seat-plate, 12, which is free to be moved is placed below the separating line, 10, and so as to underlap the two abutting rail-ends, and means are provided to raise said seat-plate upward against the rail-base, 8, and cause the plate to support the rail-ends.

I employ two supporting stringers each consisting of two ends or arms, 13, of angle-iron, shown in cross-section in Fig. 4; one of the angle-flanges of arm, 13, at each end rests on top of the rail-base, 8, at one side of the vertical web, 9, and the other angle-flange of said arm, 13, bears against the vertical web. On the opposite side of the 75 vertical web, 9, of the track-rail the two angle-flanges of the other supporting arm, 13, are likewise positioned, and bolts, 14, pass through the web, 9, and two flanges; each bolt has a head, 15, and a screw-nut, 16, and thereby the rail-web, 9, is clamped by the opposite arms, 13, of the two supporting stringers. By reference to the left-hand end of Fig. 2, it will be seen each bolt, 14, extends through a slot, 17, formed in the 80 vertical web, 9, of the rail; these slots permit the longitudinal expansion and contraction of track-rails which takes place in very warm and cold weather.

In addition to the two straight ends, 13, 90 each supporting stringer also has an outward or laterally-bent portion, 18, intermediate of said straight ends. While the straight ends, 13, rest on the base, 8, of the rail the laterally-bent part, 18, stands off 95 from the rail-base, as seen in the top plan view of Fig. 2; the said two laterally-bent parts are positioned alongside of the abutting ends of the track-rails—one part being at one side of the rails and the other at the 100 opposite side. A suspensory bar, 19, has two upward-extending arms, 20, each of which is provided at its upper end with a lateral hook, 21, that takes over and rests on the top of said laterally-bent part, 18. The 105 lower suspensory part 19, of the bar is below the abutting rail-ends, and rail-base, 8, and also below the seat-plate, 12; the bar extends crosswise, as seen in Fig. 3. This suspensory bar at its center has a screw- 110

threaded hole and a vertically-positioned screw, 22 enters the hole at its bottom and points upward and turns in said hole. The upper end of the screw 22, impinges and 5 presses upward against the bottom of the movable seat-plate. The lower end of the screw has a head 23, adapted to be grasped by a wrench to facilitate turning. The screw is provided with a spring-pawl, 24, 10 which engages with suitable ratchet-teeth, 25, fixed on the suspensory bar, 19, and this pawl and ratchet device prevents the screw from loosening or turning backward.

It will be understood from this description 15 that the seat-plate, 12, underlaps the two rail-ends and that by turning the screw, 22, the said plate will be pressed upward and will support the abutting rail ends; this support is gained from the two stringers, 13, 18, 20 extending longitudinally on opposite sides of the track-rail, 7.

In Figs. 1 and 2 two small lugs, 26, are shown on the top edge of the laterally-bent part, 18, and the lateral hook, 21, of the 25 suspensory bar, 19, takes position between said two lugs. Instead of a screw, such as 22, shown in Fig. 3, to raise the seat-plate, other means may be employed for this purpose, for instance, a cam-lever, such as, 27, 30 shown in Figs. 5 and 6 as a modification.

This cam-lever has trunnions, 28, that are pivoted in bearings in the suspensory bar, 19; the cam-head, 27, bears under the seat-plate, 12, and a cam-lever, 30, projects laterally. By imparting a vertical movement 35 to the cam-lever, 30, the seat-plate, 12, may be raised or lowered under the rail-ends.

Having described the structure of the rail-end supporter and its operation, what I 40 desire to secure by Letters Patent is—

1. The combination in a supporter for rail-ends, of two abutting track-rails having a vertical web and a rail-base whose flanges project at each side; two stringers each consisting of two straight ends that rest on top 45

of said rail-base flange, and provided intermediate of said straight ends with a laterally-bent part, 18, which stands off from said rail-base flange—one of said stringers being at one side of the two track-rails and the other stringer at the opposite side; a suspensory bar extending crosswise below the abutting rail-ends and having two upward-extending arms each of said arms being engaged with one of the said laterally-bent 55 parts; a movable seat-plate between the rail-base and said suspensory bar; and a screw vertically positioned through the suspensory bar and adapted to press upwardly against the movable seat-plate and cause the latter 60 to support the abutting rail-ends.

2. The combination in a supporter for rail-ends; of two longitudinal stringers one being secured at one side of two abutting track-rails and the other stringer at the opposite 65 side; a suspensory bar extending crosswise below the two abutted rail-ends and having two upward-extending arms each of which engages with one of said longitudinal stringers; a movable seat-plate above the suspensory bar, and below the two abutted rail-ends, and means on the suspensory bar to press the seat-plate upward against the bottoms of the two abutted track-rails. 70

3. A supporter for abutting ends of track 75 rails, having in combination two longitudinal stringers one of which is at each side of the abutted track-rails; a bar extended crosswise below the two abutted track-rails; means to connect the crosswise bar with both 80 longitudinal stringers, and means on the crosswise bar to press upwardly against the two abutted track-rails.

In testimony whereof I affix my signature in the presence of two witnesses.

JAMES M. HILL.
